US00D592619S

(12) **United States Design Patent**
Woo et al.

(10) **Patent No.:** **US D592,619 S**
(45) **Date of Patent:** **** May 19, 2009**

(54) **SET TOP BOX**

(75) Inventors: **Sang-Sung Woo**, Seoul (KR); **Chul-Yong Cho**, Seoul (KR); **Bum-Ho Chun**, Seoul (KR); **So-Yoon Jeon**, Kyunggi-do (KR); **Dae-Joung Kim**, Seoul (KR); **Sung-Jin Yum**, Kyunggi-do (KR); **Tae-Hun Kim**, Seoul (KR)

(73) Assignee: **Samsung Electronics Co., Ltd.**, Kyunggi-do (KR)

(**) Term: **14 Years**

(21) Appl. No.: **29/308,614**

(22) Filed: **Jun. 26, 2008**

(51) **LOC (9) Cl.** **14-03**

(52) **U.S. Cl.** **D14/125**

(58) **Field of Classification Search** D14/125-134, D14/239, 371, 136, 374-377; 312/7.2; 348/836, 348/838, 180, 184, 325, 739; 341/2; 248/917-924, 248/465, 123.11; 345/104, 133, 156, 168, 345/87, 173, 169; 349/1, 2, 11, 62; 720/605, 720/669, 600, 655, 99, 197; 455/344-347

(57) **CLAIM**

The ornamental design for a set top box, as shown and described.

DESCRIPTION

FIG. 1 is a top front perspective view of a set top box showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict environmental subject matter only and form no part of the claimed design.
